UNITED STATES PATENT OFFICE.

THOMAS BELL STEWART, WILLIAM HERBERT TURNER, AND ROWLAND EDWARD DIXON, OF LEEDS, ENGLAND.

AUTOMATIC APPARATUS FOR CONTROLLING AND OPERATING THE POINTS OF ELECTRIC RAILWAYS OR TRAMWAYS.

SPECIFICATION forming part of Letters Patent No. 747,795, dated December 22, 1903.

Application filed April 1, 1902. Serial No. 100,952. (No model.)

To all whom it may concern:

Be it known that we, THOMAS BELL STEWART, WILLIAM HERBERT TURNER, and ROWLAND EDWARD DIXON, subjects of the King of Great Britain and Ireland, residing at Leeds, in the county of York, England, have invented a new and useful Automatic Apparatus for Controlling and Operating the Points of Electric Railways or Tramways, of which the following is a specification.

This invention relates to overhead-cable electric railways and tramways, the object being to provide an improved apparatus for automatically controlling and operating the points of such electric railways and tramways. The points are operated automatically by means of an electromagnetic solenoid, which is suitably situated beside or near the rail and is controlled from the car by means of an overhead apparatus actuated by the trolley. The solenoid is provided with suitable mechanical connections to the rail-point and to the overhead point or frog, these connections being so arranged that they may be operated by hand when required independent of the electrical apparatus.

Our invention is illustrated in the accompanying drawings, in which—

Figure 1 is a plan showing position of apparatus. Fig. 2 is a side elevation showing method of controlling same from the car. Fig. 3 is a side elevation of solenoid and its connections for operating the points. Fig. 4 is a detail plan view of the frog *e*, showing the connection of the wire *i* with the overhead point. Fig. 5 is a detail end view of the switch *n*.

Similar letters and numerals refer to similar parts throughout the several views.

The core *a* of the solenoid *b* is connected to the rail-point *c* by means of rod *d* or other connection and is also connected to the overhead point or frog *e* by means of hand-lever *f*, pivot 14, pin 15, rod *g*, lever *h*, and wire *i*. These connections may be operated by hand when required by means of the hand-lever *f* independent of the electrical apparatus.

The solenoid *b* is controlled from the car by means of a switch or switches *k* and is operated (when one of the switches *k* is on) by the

trolley-head of the car making contact with overhead switches carried by the trolley wires or cables. One of these overhead switches *l* is arranged on the main cable *m* in front of the frog or point *e* and the other overhead switch *n* on the branch cable *o* behind the frog or point *e*. Thus when a main-line car comes along the car-switches *k* are both off, and the car consequently passes along the main line without interfering with the points 60 in any way. When a branch-line car comes along, the car-switch *k* is put on before arriving at the first overhead switch *l*. On reaching the said overhead switch *l* the trolley-head makes contact, and the rail-point *c* and 65 overhead point *e* are automatically turned, so as to connect with the branch line, the points being automatically reversed when the car passes into the branch line, and the trolley-head makes contact with the second overhead switch *n*. 70

The switches *l* and *n* are both alike, and the description will therefore be confined to the switch *n*. The switch *n* has arms *w*, which are pivoted to a block of insulating material *w'*. The trolley-head has insulated contact-plates *v*, which move the arms *w* apart and place them in contact with the switch-block *n'*, with which the wire *g* is connected. The trolley-wheel *v'* runs on the cable *m* and is normally insulated from the contact-plates *v*, the connection between them being effected by means of the wires *g* and the switch *k* on the car. When the lower ends of the wires *g* are connected by closing 80 the switch *k*, the current passes from the cable *m* to the wire *g*. The switches *l* and *n* are in electrical connection with the switch-board 3 by means of lead-wires 4, 5, fuses 6, 7, and magnets 8, 9. The lead-wire 10 from the 85 overhead cable connects with the solenoid *b* by means of fuse 11 and main switch 12 when closed, the whole being preferably inclosed within the box 13. The contact-plates of the switch 12, which are secured to the switch-board 3, are separated by insulating material 50, so that the switch-lever bridges them when the switch is closed. 90

The action of the apparatus is as follows: A main-line car having its switches *k* both 100

off passes along the main line without interfering with the points in any way. When a branch-line car comes along, the driver puts on his car-switch *k*, so that when the trolley-head 5 makes contact with the first overhead switch *l* a current passes through the lead-wire 4, exciting the magnet 8 and closing the switch 12, the current then passing from the magnet 8 to earth through the wire *E*. This allows 10 a second current to pass from the lead-wire 10 through the fuse 11, switch 12, wire *b'*, and solenoid *b* to earth. This current excites the solenoid *b*, which draws in the core *a* and actuates the rail-point *c*, at the same time 15 by means of the wire *i* and its connections actuating the overhead point or frog *e*. When the trolley-head makes contact with the second overhead switch *n*, a third current passes through the lead-wire 5, exciting 20 the magnet 9 and opening the switch 12, this current also passing from the magnet 9 to earth by the wire *E*. This breaks the main circuit through the lead-wire 10 and allows the core *a* to be drawn out again by means 25 of a suitable spring, weight, or other convenient device, thus automatically reversing the rail-point *c*, which permits the overhead point *e* to be automatically reversed by means 30 of a suitable spring, such as 16, in the ordinary manner.

We do not claim the specific construction

of any of the switches, as they, including all the switch mechanism on the switchboard 3, are of any approved construction and operate in the usual manner.

35

What we claim as our invention, and desire to secure by Letters Patent, is—

In an electric railroad, the combination, with a main line, and a branch line having a switch-point *c*; of a main conductor having 40 an overhead switch *l*, a branch conductor having an overhead switch end, and an overhead point *e* at the junction of the said conductors, a solenoid *b* and connections for operating the points *c* and *e*, electromagnets 45 8 and 9, a switch 12 operated by the said electromagnets, connections between the switches *l* and *n* and the electromagnets 8 and 9 respectively, a connection between the point *e* and the said solenoid through the said switch 50 12, and a switch *k* on the car for controlling the circuit.

In testimony whereof we have signed our names to this specification in the presence of two subscribing witnesses.

THOMAS BELL STEWART.
